UNITED STATES PATENT OFFICE.

OSCAR MARTIN CARTER, OF HOUSTON, TEXAS.

EXPANSIVE AND CONTRACTIVE WELL-DRILL.

1,271,275.

Specification of Letters Patent. Patented July 2, 1918.

Application filed January 5, 1918. Serial No. 210,586.

To all whom it may concern:

Be it known that I, OSCAR M. CARTER, a citizen of the United States, and a resident of Houston, in the county of Harris and State of Texas, have invented a new and useful Improvement in Expansive and Contractive Well-Drills, of which the following is a specification.

My invention relates to improvements in well drills, being more particularly an improvement in drills of the expansive and contractive bit type, and it consists in the constructions, combinations and arrangements herein described and claimed.

An object of my invention is to provide a drill of the type described, including as the essential feature a carrier casing having the expansive and contractive drill bits mounted therein with rack plates for extending the bits, said casing being adapted to be lowered into the drill stem and also to be raised out of operative position, without involving the danger of scarifying the well bore.

Another object of the invention resides in the provision of the latch which coöperates with the rack plates in locking the bit extending pinions after they have been acted upon by the rack plates.

Another object of the invention is to provide novel means for directing a stream of water and mud against the drill bits, to keep them from becoming clogged.

Other objects and advantages will appear in the following specification, reference being had to the accompanying drawings in which:

Figure 1 is a perspective view of the improved well drill, the carrier casing being shown in section,

Fig. 2 is a longitudinal section taken substantially on the line 2—2 of Fig. 1,

Figs. 3, 4, 5, 6, 7, 8 and 9 are cross sections on the lines 3—3, 4—4, 5—5, 6—6, 7—7, 8—8 and 9—9 of Fig. 1,

Fig. 10 is a side elevation showing the improved well drill at the bottom of the drill stem, and also showing the lowering tongs,

Fig. 11 is a vertical section of parts shown in Fig. 10, one of the carrier side plates being removed,

Fig. 12 is a side elevation of the well drill, the carrier casing being omitted and the bits being in the retracted position,

Fig. 13 is a detail side elevation of a por-

tion of the well drill illustrating the action of the cleansing stream.

Fig. 14 is a detail perspective view of the carrier casing,

Fig. 15 is a detail perspective view of the lower end of the drill stem,

Fig. 16 is a section on the line 16—16 of Fig. 13,

Figs. 17 and 18 are detail perspective views of portions of the carrier casing, and

Fig. 19 is a detail view illustrating the raising tongs employed in connection with the device.

In carrying out my invention I provide a drill stem 1 which consists of a plurality of pipe sections joined together by couplings or by any other suitable means, the drill stem having an enlarged head 2 at the bottom, into which the drill bits 3 and 4 expand. The drill bits 3 and 4 are supported in a carrier casing 5. Rack plates 6 and 7 are fixed in the carrier casing 5 by means of screws 8 or some other similar means.

The rack plates 6 and 7 project beyond the upper edge of the carrier casing 5, and are so formed and arranged, that a latch 9 is movably disposed in the center of the body of the composite rack plates, the latch having a stem 10 provided with a head 11, by means of which the well drill is gripped by the lowering tongs shown in Fig. 10. Referring briefly to Fig. 10, it will be observed that the lowering tongs consist of a body 12 arranged at the top to receive the rope or cable 13 by means of which the drill is lowered through the drill stem 1 to the bottom of the well. A novel form of raising tongs is also employed in connection with the device. These tongs are illustrated in Fig. 19 and will presently be more fully explained.

The tong arms 14 are pivoted to the lower end of the body 12. The upper portions of the arms are made comparatively long and possess considerable weight. When the well drill is lowered and reaches the proper position at the bottom of the stem 1, tension on the rope 13 is loosened, whereupon the body 12 moves down, the weighted arms 14 move out, and the conical head 11 on the stem 10 is released. The lowering tongs may then be withdrawn from the drill stem 1, and the well drill will have been placed in the proper position, as will hereinafter appear.

The rack plates 6 and 7 have rack extensions 15 and 16 respectively. The ex-

tension 15 meshes with a pinion 17, while the extension 16 meshes with a pinion 18. Both pinions are mounted on a shaft 19, supported at its ends in carrier side plates 20.

A rack 21 is formed on top of each of a pair of bit holders 22 in which the bits 3 and 4 are secured by the bolts 23. The pinions 17 and 18 mesh with the racks 21 of the respective bit holders, and are adapted to extend and retract the bits according to the direction of movement in either a downward or upward direction, of the rack plates. The latch 9 simultaneously engages notches 24 and 25 in the pinions 17 and 18, when the bits 3 and 4 are in the extended position shown in Fig. 1, and thereby lock the bits in this position during the operation of the drill.

The rack plates 6 and 7 are fastened together by screws 26 and thus form a composite body which is provided with a passage 27 in the center, in which the latch 9 slides. The latch 9 is the indirect controlling agent by which the extension and retraction of the bits 3 and 4 is obtained. A dog 28 is virtually the connecting link between the latch and the rack plates, and by means of its coöoperative function with the latch, secures the shifting of the rack plates in a certain portion of the movement of the latch.

A nose 29 is formed on the dog 28 near the pivot 30. The nose 29 is disposed in the dog slot 31 formed at one side of the latch 9. The dog 28 is located in a chamber 32 formed by cutting away adjacent portions of the composite rack plates, as clearly shown in Fig. 1. The dog 28 also has a mortise 33 at the exposed end, into which a lever 34 is adapted to be fitted when it is desired to free the dog from its clamped engagement with the latch 9, as shown in Fig. 12. This feature will be more fully explained later.

Straps 35 bridge the separated portions of the rack plates, and hold them together by virtue of the screws which secure the straps in place on said portions. It will be understood that the rack plates are separated into the portions referred to, through the formation of the passage 27 in which the latch slides. The straps 35 are received in cut away portions 36 of the edges of the latch 9.

A pin 37 disposed in a slot 38 in the latch 9, limits the up and down movement of the latch. The movement of the rack plates 6 and 7 is also limited by means of pins 39 disposed in slots 40 of the portions of the respective plates.

The occupancy of the pins 37 and 39 in the slots 38 and 40, indicates that the latch 9, and the rack plates are adapted to be locked up and down. As has been indicated,

this movement of the latch and rack plates, serves to lock and unlock the pinions in one instance, and rotate the same pinions in either one or the other direction, in the other instance. The bit holders 22 are extended when the rack plates move down, and the pinions are rotated correspondingly.

A rib 41 on each of the side plates 20, occupies a guide slot 42 in the companion bit holder. The bit holders slide upon the ribs 75 and also keep the bit holders from dropping out of engagement with the pinions. Each bit holder has a peculiar shape, in that it includes an offset bracket 43, which receives the bit, and in which the bit is secured by 80 the bolts 23. The offset bracket 43 provides a shoulder 44 which abuts the lower edge of the side plate 20 thereby securing a more firm support for the bit holder, which further tends to keep the bit holder from oscillating on the side plate.

In this connection the peculiar shape of the lower end of each of the side plates should be observed. Attention is directed to Figs. 12 and 17. The side plate 20 has an 90 enlarged head 45 which in its formation on the plate, provides a shoulder 46 abutting one corner of an opening 47 of the carrier casing 5. This construction is clearly shown in Fig. 14. Referring again to Fig. 17 it 95 will be seen that the head 45 is beveled at 48. The bevel occupies approximately only one-half of the width of the head. Opposite portions of the heads of the side plates are beveled. In other words, the portion of 100 the head in Fig. 17 nearest the observer, being beveled, the diametrically opposite portion of the head of the other plate will be beveled.

The bevels 48 coöperate in directing a 105 stream of water and mud under pressure against the bits 3 and 4. This stream is more forcibly directed by the aid of similarly beveled portions 49 of closure plates 50 secured in the bottom of the carrier casing 5, by screws 51 or other means. The location of the closure plates is shown in Fig. 16, and one of the closure plates is illustrated in Fig. 18. The bevels 49 also occur at diametrically opposite points, so that there may be one of the bevels 49 opposite each of the bevels 48 on the respective side plates 20. These beveled portions in opposing each other, form relatively narrow slits or orifices 52 through which the water and mud flows 110 115 at great pressure and speed.

Lugs 53 formed on the lower edge of the enlarged head 2 of the drill stem 1, support the carrier casing 5 as clearly shown in Fig. 16. The lugs include shanks which occupy 125 recesses on the inside surface of the head and are secured therein by screws. The lugs are sometimes broken off, and then the screws may be removed so that the remaining portion of the shank may be taken out 130

and another lug put in its place. The lugs are made of some brittle material and are smaller where they join the shanks, so as to facilitate breaking them off flush with the inside of the enlarged head. This is done by dropping down a heavy weight with a rope attached to withdraw same so that a strainer of a smaller drill stem and bit may be passed through unimpeded and continue 10 the hole to a greater depth.

Slots 54 are cut into the lower edge of the drill stem head 2 and the upper edges of the slots are reinforced by bosses 55 which are cast on the outside of the head as shown 15 in Fig. 15. The slots 54 coincide with the openings 47 in the carrier casing 5. The outer portions of the bit holders 22 project into the slots 54 when the bits are in the extended positions, and lock the bits in 20 place. This position of the parts is shown in Figs. 10, 11 and 13. Guide cams 56 are formed on the inside of the drill stem head 2, and occupy the surface between the slots, as clearly shown in Fig. 15.

25 The guide cams 56 guide the drill bits to the slots 54. As the drill is lowered into the drill stem, and when the drill bits which in the meantime become extended until they engage the surface of the drill stem, reach 30 the enlarged head 2, they consequently become extended still farther, ultimately reaching the guide cams 26 and are thereby guided in either one or the other direction, to the slots 54.

35 Fig. 19 formerly referred to, illustrates how a novel form of raising tongs is employed to withdraw the drill carrier from the drill stem. These tongs consist of the members 14^a pivoted together on the bottom 40 of the body 12. A rope 13 is secured to the body. The free ends of the tong members 14^a are formed into hooks 14^b which are adapted to grapple the conical head 11 on the stem 10. It will readily be observed that 45 the nature of the tongs makes the members 14^a drop to the normally closed position. When the tongs are now lowered into the drill stem, the hooks 14^b upon striking the head 11, will separate until, upon pulling 50 up on the tongs, they will engage the head as shown in Fig. 19. Both forms of the tongs illustrated in Figs. 10 and 19 have their particular value when used in connection with this particular form of drill.

55 As has previously been fully brought out the tongs illustrated in Fig. 10 are primarily adapted to lowering the drill. It will also be evident that the tongs in Fig. 19 are primarily adapted to raising the drill out of the 60 drill stem.

The operation of the device is as follows: The tongs 14 grip the head 11 of the stem 10, and the drill is lowered into the drill stem 1 by the rope 13. Two distinct movements or actions now follow. The first ac-

tion occurs after the dog 28 is tripped. The dog is tripped by inserting the lever 34 in the mortise 33, and pressing upward. The carrier 5 is thus lifted until the nose 29 of the dog slips entirely out of the dog slot 31. The gear racks are then free to descend, partly expanding the bits so that they rub against the inside of the drill stem. The carrier 5 is further lowered until it rests on the lugs 53, whereupon by releasing tension on the rope, the bits expand to the fullest extent through the slots 54.

The second action occurs when the latch 9 is lowered to engage the alining notches 24 in the pinions 17 and 18. The carrier 5 and the bits now being in the final position, the carrier and the side plates 20 become the relatively stationary member. Further releasing of the rope permits the latch 9 to lower as described. The bits are now locked in the operating position.

The action of the dog 28 should also be understood. The dog is disposed in the position indicated in Fig. 12, when the bits are in the retracted position and when the drill is on the surface. The nose 29 is disengaged from the dog slot 31 in the latch 9 by the use of the lever 34. An upward pressure on the lever first drives the latch 9 down a short distance in riding past the lower edge of the slot, but this having once been done, the weight of the carrier causes the carrier to descend a limited distance carrying the dog entirely below the dog slot. The nose of the dog is beveled on top, and this beveled surface is adapted to lie parallel with the latch passage to enable the dog slot 31 in the latch 9 to move to a position beyond the dog. There is now perfect freedom between the latch and the bit carrier during the descent. The descent of the carrier is limited by the engagement of the bits with the inside of the drill stem as formerly explained, and the function of the rack plates 6 and 7 remain latent until the outlets of the bits are reached when they drop by gravity. The spring 28^a holds the dog in the normal position. The dog is pivoted off center and will ordinarily assume the normal position by gravity. But to obviate the possibility of sticking, the spring 28^a is made to bear on top of the dog and thus insure the proper working of the dog.

The real function of the dog 28 is performed principally when the drill is withdrawn from the drill stem. The occupation by the nose 29 of the dog slot 31 makes the two part motion of the latch 9 and the rack plates 6 and 7, possible. In withdrawing the drill from the drill stem, the rope 13 is pulled upon until the lower edge of the nose engages the base of the slot 31. So much of the initial action serves to withdraw the end of the latch 9 from engagement with the 12

alining slots 24 of the pinions, so that they are free to rotate as will presently appear.

The nose 29 now forms a solid connection between the rack plates and the latch.

5 A continued pull on the rope 13 now serves to move the rack plates upwardly, so that the rack extensions 15 and 16 rotate the pinions 17 and 18, and consequently retract the bits 3 and 4. It now follows, that since the bits 10 are encompassed by the carrier casing, the entire drill may be withdrawn from the drill stem, until it reaches the surface.

It will be observed that the slot 38 in the latch 9 is longer than the slots 40 in the rack 15 plates. This extra length of the slot 38 is necessary to permit the two part motion just described. Returning briefly to the manner of clearing the bits of accumulated matter during operation, water and mud is 20 forced down the inside of the drill stem, and passes through the orifices 52 under great pressure against the sides of the bits as indicated by the arrows in Fig. 16, whereupon the water and mud stream returns to 25 the top of the well on the outside of the drill stem 1.

This action of the water and mud leads to a consideration of one of the important features of the invention. The mud naturally 30 seals the crevices and rough places in the surface of the bore of the well, but in instances where drills are used which have projecting portions, the sides of the bore are scarified on withdrawing the drilling tool. 35 A moment's consideration will make it evident that the sides of the bore cannot be injured when the type of tool illustrated in the drawings is employed. The tool is withdrawn on the inside of the drill stem and 40 consequently does not come in contact with the bore.

Incidentally the edges of the carrier casing 5 are beveled or rounded to prevent the possibility of catching, when lowering the drill. While the construction and arrangement of the device as illustrated in the accompanying drawings is that of a generally preferred form, obviously modifications and changes may be made without departing 50 from the spirit of the invention or the scope of the claims.

I claim:—

1. A drill, including a carrier casing having extensible bits, adapted to be lowered 55 into a drill stem with slots in the end, and gravity operated means carried by and rendered latent to extend the bits, before introducing the drill into the stem, said means urging the bits against the wall of the stem 60 during the act of lowering, and becoming active to extend the bits when the slots are reached.

2. In a drill, a cable including gripping means for supporting the drill, extensible 65 bits embodied in the drill, gravity operated

means for extending the bits, and releasable means normally restraining the gravity operated means.

3. A drill, including a carrier casing having extensible bits, adapted to be lowered 70 into a drill stem with slots in the end, means carried by and rendered latent to extend the bits, before introducing the drill into the stem, said means urging the bits against the wall of the stem during the act of lowering, 75 and becoming active to extend the bits when the slots are reached, and independently movable means carried by the carrier casing, providing the attaching member for receiving a lowering tongs, being capable of movement with respect to said bit extending means upon being released, to lock the bits in the extended positions.

4. In a drill, extensible bits, gravity operated means for extending the bits, means 80 for engaging and locking said means upon arrival of the bits in the extended position, and means for simultaneously guiding and supporting the bits.

5. In a drill, extensible bits, means operated by gravity for extending the bits, and means operated by gravity for locking said means and preventing the bits from retracting while said locking means is in engagement with the bit extending means. 90

6. In a drill, a drill stem with slots, a carrier casing occupying an operative position at the bottom of said drill stem, bits carried by the carrier casing and extended through the slots, means for retracting the bits 100 through the slots, means providing an attaching member for a raising tongs and locking the bits in the extended position, and means forming a connection between the locking means and said retracting means 105 on the initial unlocking movement of said locking means in raising the drill, said retracting means then moving the locking means on making said connection, to retract the bits.

7. In a drill, a bit holder including a rack, a pinion engaging the rack, and a rack bar including a rack extension in engagement with said pinion, said rack extension rotating the pinion and extending the bit holder 115 upon movement of the rack bar by gravity.

8. In a drill, a bit holder including a rack, a pinion engaging the rack, a rack bar including a rack extension in engagement with said pinion, said rack extension rotating the 120 pinion and extending the bit holder upon movement of the rack bar by gravity, and means engaging a portion of the rack bar for limiting the movement of the rack bar.

9. In a drill, a bit holder including a rack, 125 a pinion engaging the rack, a rack bar including a rack, in engagement with said pinion, said rack extension rotating the pinion and extending the bit holder upon movement of the rack bar by gravity, means en- 130

gaging a portion of the rack bar for limiting the movement thereof, and means partly incasing the rack bar and supporting the limiting means.

5 10. In a drill, a carrier casing, side plates fixed in spaced relationship in said casing, bit carriers slidably supported on said side plates, and gravity operated means movable between the side plates for extending the 10 bits.

11. In a drill, a carrier casing, side plates fixed in spaced relationship in the carrier casing, a bit holder slidably transversely of the side plates, means for supporting the bit holder on the adjacent side plate, revoluble means engaging the bit holder, a gravity operated member including a portion engaging the revoluble member for turning said member, said gravity member being movable between said side plates, and means carried by the side plates passing through said gravity operated member for guiding it in its movements.

12. In a drill, a carrier casing, side plates fixed in spaced relationship in the carrier casing, a transverse rib formed on each side plate, a bit holder having a guide slot receiving the rib of one of the plates, a rack formed on the bit holder, a pinion engaging the rack, a pinion supporting shaft mounted in the side plates, a rack plate movable between the side plates and having a slot, a rack extension carried by the rack plate engaging the pinion, and a guide pin fixed in the side plates and passing through said slot.

13. In a drill, oppositely extensionable bit holders having rack portions, a pinion meshing with each rack and oppositely rotatable on a common shaft, each pinion having a notch, a pair of rack plates each having a rack extension engaging one of the pinions, and a latch movable relatively to the rack plates and arranged to enter said notches when in alinement, upon rotation of the pinions by the rack extensions under the action of gravity.

14. In a drill, oppositely extensible bit holders including racks, oppositely rotatable pinions engaging the racks each pinion having a slot, a common shaft for the pinions, rack plates including rack extensions engaging the pinions and rotating them in one direction upon movement of the rack plates by gravity, and a latch movable with the rack plates through a portion of their movement and arranged for additional movement when the rack plates come to rest, and enter the then alined slots of the pinions.

15. In a drill, a bit holder having a rack, a pinion engaging a rack, said pinion having a notch, a rack plate for rotating the pinion, a latch engaging the notch and locking the bit holder to the extended position, and means carried by the rack plate engageable

by a portion of the latch upon withdrawal of the latch from said notch, to cause the rack plate to be carried therewith upon continued movement of the latch.

16. In a drill, a bit holder operating pinion having a notch, a rack plate for rotating the pinion to retract the bit holder upon the upward movement of the rack plate, a latch engaging the notch to lock the bit holder in the extended position, the latch being withdrawn from the notch on the initial movement in withdrawing the drill, and engageable means carried by the rack plate for abutting a portion of the latch to cause the rack plate to move upward on continued movement of the latch.

17. In a drill, a bit holder operating pinion having a notch, a rack plate for rotating the pinion to retract the bit holder upon the upward movement of the rack plate, a latch engaging the notch to lock the bit holder in the extended position, the latch being withdrawn from the notch on the initial movement in withdrawing the drill, engageable means carried by the rack plate for abutting a portion of the latch to cause the rack plate to move upward on continued movement of the latch and means for guiding and limiting the movement of the rack plate.

18. In a drill, a vertically movable rack plate, a relatively inovable latch having a slot, and a dog carried by the rack plate, including a nose occupying the slot and adapted to be engaged by the base of the slot to carry the rack plate with the latch upon continued movement of the latch in the vertical direction.

19. In a drill, a rack plate having a chamber, a dog pivoted in the chamber, having a nose projecting beyond an edge of the rack plate, and a latch movable relatively with respect to the rack plate, and having a dog slot receiving the nose.

20. In a drill, a rack plate having a chamber, a dog pivoted in the chamber, having a nose projecting beyond an edge of the rack plate, a latch movable relatively with respect to the rack plate, and having a dog slot receiving the nose, and guiding means holding the latch in proper relationship to the rack plate.

21. In a drill, a rack plate having a central passage, with a chamber opening into the passage and to one edge of the rack plate, a dog pivoted in the chamber including a mortise accessible from the edge opening of the chamber and adapted to receive a lever, the dog having a nose projecting into the central passage, and a latch movable in said passage, having a dog slot adapted to receive the nose.

22. In a drill, a pair of rack plates including separate members spaced apart to leave a central passage, straps secured to the sep-

- arate members to form a composite rack plate body, adjacent portions of the rack plates being cut away to form a chamber at one side of said passage, a dog pivoted in 5 said chamber with a nose projecting into said passage, and a latch occupying the central passage with a slot receiving the nose and having cut-away portions receiving the straps.
- 10 23. In a drill, a carrier casing, side plates fixed in spaced relationship in said casing, rack plates slideable between the side plates and having slots, pins carried by the side plates occupying the slots to limit the movement of the rack plates, a latch slideable between portions of the rack plates and having a slot longer than the rack plate slots to permit additional relative movement of the latch with respect to the rack plates, and a 15 pin mounted in the carrier casing and occupying said slot.
24. In a drill, a carrier casing including extensible bits, supporting means for the extensible bits, and means mutually carried by 20 the carrier casing and said bit supporting means, for directing a stream of liquid against the bits.
25. In a drill, a carrier casing including extensible bits, means including carrier side 25 plates, for supporting the extensible bits, and means carried by the carrier casing and said bit supporting means forming orifices for directing a stream of liquid in opposite directions against the bits.
- 30 26. In a drill, the combination of a drill stem having an enlarged head provided with opposed slots, a carrier casing including bit carriers adapted to be extended into locking engagement with said enlarged head by entrance into the slots, and lugs for supporting the carrier casing.
27. In a drill, a drill stem having an enlarged head provided with opposed slots, bits adapted to be lowered into the stem, 35 gravity operative means for extending the bits, a lowering cable including a member movable with respect to said extending means, and a dog arranged to prevent initial relative motion between the movable member and the gravity operated means, but adapted to be tripped to permit said relative motion of the gravity operative means to extend the bits into contact with said stem while lowering the bits, said bits extending 40 into said opposed slots upon reaching the enlarged head.
28. In a drill, a drill stem, a carrier casing including extensible bits adapted to be lowered into the drill stem, and breakable supporting members for supporting the carrier casing.
- 45 29. In a drill, a drill stem having a recess at the lower edge, an inwardly extending lug including a shank occupying and secured in the recess, the neck joining the lug and the shank being weakened to facilitate breaking of the lug, and a carrier casing adapted to be lowered into the drill stem and rest upon the lug under normal conditions.
30. In a drill, a carrier casing having opposed openings at the bottom, a side plate mounted in the carrier casing, said plate including an enlarged head providing shoulders occupying opposite corners of said openings, a rib formed transversely of the head, 70 a bit carrier including a guide slot receiving the rib, and means for extending the bit carrier on the rib through one of the openings.
31. In a drill, a drill stem including an enlarged head having a slot, a carrier casing 75 having an opening adapted to align with said slot, a side plate fixed in the carrier casing and having an enlarged head providing shoulders occupying opposite corners of said openings, a rib formed transversely of said head, a bit holder having a guide slot receiving the rib, and means for moving the bit holder upon the rib into the aligned opening and slot.
32. In a drill, a carrier casing, side plates fixed in said casing, slideable rack plates mounted between the side plates, extensible bits, interposed means for extending the bits through movement of the rack plates, a latch for locking said means, a stem carried 80 by the latch, and a gripping head mounted on the stem.
33. In a drill, a carrier, extensible bits, means relatively movable by gravity with respect to the carrier for extending the bits, 100 a member relatively movable with respect to said gravity movable means and adapted to be supported on a lowering cable, and an interposed member mounted on the gravity movable means engaging the relatively movable member, said interposed member being adapted to be disengaged from said relatively movable member to permit the partial operation of said gravity movable means.
34. In a drill, a drill stem, a carrier adapted to be lowered into said stem, a latch carried by the carrier and arranged to receive the lowering cable, laterally extensible bits supported on the carrier, means operated by gravity to extend the bits and movable with respect to said latch, and a dog pivoted on said means normally engaging the latch to prevent the gravity operation of said means, said dog being adapted to be tripped out of engagement with the latch to permit a portion of the gravity operation of said means and extend said bits into engagement with said drill stem.
35. In a drill, the combination with the 125 drill stem, of a latch adapted to receive the tongs of a lowering cable, bits adapted to be extended into engagement with said stem during the lowering of the drill, gravity operated bit extending means, and a dog 130

- carried by said means normally engaging said latch to hold the bits in the retracted position, said dog being adapted to be tripped to a disengaging position to permit 5 the weight of said gravity operated means to be in active position for the further extension of the bits.
36. In a drill, bits adapted to occupy the extended position, gravity operated movable means for extending the bits, combined means acting as a drill support in lowering the drill, and as locking means engaging the movable extending means when the bits are extended, said combined means being initially movable in retracting from the locking engagement with said movable extending means in raising the drill, and means arranged to provide a fixed connection between said combined means and said gravity operated means, after a predetermined initial movement of said combined means, to actuate said gravity operated means in the other direction on continued movement of said combined means, and retract the bits.
37. In a drill, a carrier casing having opposed openings, and carrier side plates mounted in said casing, each being formed with an enlarged head to provide a pair of shoulders for resting in said openings, each head having a beveled portion directed inwardly.
38. In a drill, a carrier casing having opposed openings, carrier side plates mounted in said casing, each being formed with an enlarged head to provide a pair of shoulders for resting in said openings, each head having a beveled portion directed inwardly, and a closure plate mounted in said casing ad-
- jacent to each enlarged head, said plates having beveled portions adjoining the beveled portions of the heads to provide fluid orifices.
39. In a drill adapted to be lowered into a drill stem, extensible bits, a carrier casing including means for supporting the extensible bits, gravity operated means including composite rack plates, revoluble means including pinions adapted to be operated by said rack plates to extend the bits, a latch movable with respect to said plates and having a head adapted to receive the tongs of a lowering cable, said latch having a dog slot, and a dog pivoted on one of the rack plates with a nose adapted to occupy the dog slot, said dog including a beveled top portion adapted to lie against said latch beneath the dog slot when the carrier casing is supported by the cable tongs in lowering the drill into the stem, said rack plates being then freely suspended and pressing the bits into contact with the walls of the drill stem in readiness to fully extend the bit when the end of the drill stem is reached.
40. In a drill, the combination of a drill stem having an enlarged head provided with opposed bit slots at the end, inwardly extending lugs at the end of the head, a carrier casing adapted to be lowered into place on the lugs in the enlarged head, bits carried by the carrier casing and in contact with the inner wall of the stem in lowering, and inverted V-shaped guides between the opposed slots, adapted to direct the contacting bits toward said slots.

OSCAR MARTIN CARTER.
